DESIGN FOR A PHONOGRAPH CABINET

Ernest F. Thomson, Tuckahoe, N. Y., assignor, by
mesne assignments, to Reconstruction Finance
Corporation, Kansas City, Mo., a corporation of
the United States

Application May 28, 1946, Serial No. 130,138

Term of patent 3½ years

(Cl. D56—4)

To all whom it may concern:

Be it known that I, Ernest F. Thomson, a citizen of the Dominion of Canada, residing at Tuckahoe, Westchester County, New York, have invented a new, original, and ornamental Design for a Phonograph Cabinet, of which the following is a specification, reference being had to the accompanying drawing, forming part thereof.

In the drawing, the single figure is a perspective view of a phonograph cabinet embodying my new design.

Both sides of the design are the same.

I claim:

The ornamental design for a phonograph cabinet, as shown and described.

ERNEST F. THOMSON.
